UNITED STATES PATENT OFFICE

99,291

DESIGN FOR A CASING FOR AIR CONDITIONING APPARATUS

Edgar V. Ludwig, New York, N. Y., assignor to
American Radiator Company, New York, N. Y.,
a corporation of New Jersey

Application March 5, 1936, Serial No. 61,488

Term of patent 14 years

To all whom it may concern:

Be it known that I, Edgar V. Ludwig, a citizen
of the United States, residing at New York, in the
county of New York and State of New York, have
invented a new, original, and ornamental Design
for a Casing for Air Conditioning Apparatus, of
which the following is a specification, reference
being had to the accompanying drawing forming
part thereof.

In said drawing—

Fig. 1 is a perspective view of a casing for air

conditioning apparatus embodying my new de-
sign; and

Fig. 2 is a side elevational view of the casing
shown in Fig. 1.

I claim:

The ornamental design for a casing for air con-
ditioning apparatus, as shown.

In witness whereof, I have hereunto subscribed
my name.

EDGAR V. LUDWIG.
